(57) **CLAIM**

The ornamental design for a replaceable bin latch, as shown and described.

DESCRIPTION

FIG. 1 is a front perspective view of a replaceable bin latch showing our new design;

FIG. 2 is a back perspective view thereof;

FIG. 3 is a front elevation view thereof;

FIG. 4 is a top view thereof;

FIG. 5 is a bottom view thereof;

FIG. 6 is a left side view thereof;

FIG. 7 is a back plan view thereof; and,

FIG. 8 is a sectional view thereof, taken along line 8-8 of FIG. 3.

The right side view is a mirror image of the left side view thereof.
